COMPARTMENTED PLATE

Charles J. Chaplin, South Portland, Maine, assignor to Chaplin Corporation, South Portland, Maine, a corporation of Maine

Application March 29, 1950, Serial No. 8,835

Term of patent 14 years

(Cl. D44—15)

To all whom it may concern:

Be it known that I, Charles J. Chaplin, a citizen of the United States of America, residing at South Portland, in the county of Cumberland and State of Maine, have invented a new, original, and ornamental Design for a Compartmented Plate, of which the following is a specification, reference being had to the accompanying drawing, forming part thereof.

In the drawing:

Figure 1 is a top plan view of a compartmented plate embodying my new design; and

Figures 2 and 3 are vertical cross sectional views thereof taken respectively on lines 2—2 and 3—3 of Figure 1.

I claim:

The ornamental design for a compartmented plate, as shown.

CHARLES J. CHAPLIN.
